UNITED STATES PATENT OFFICE.

ELIGAH HENRY DUCKETT, OF PINE BLUFF, ARKANSAS, ASSIGNOR OF ONE-HALF TO
EDWIN BOYCE, OF PINE BLUFF, ARKANSAS.

WELL-CAPPING DEVICE.

1,404,350.

Specification of Letters Patent. Patented Jan. 24, 1922.

Application filed May 2, 1921. Serial No. 466,147.

To all whom it may concern:

Be it known that I, ELIGAH H. DUCKETT, a citizen of the United States, residing at Pine Bluff, in the county of Jefferson and State 5 of Arkansas, have invented certain new and useful Improvements in Well-Capping Devices; and I do declare the following to be a full, clear, and exact description of the invention, such as will enable others skilled 10 in the art to which it appertains to make and use the same.

My invention relates to improvements in devices for capping oil wells when oil is struck and forcible discharge thereof takes 15 place.

One object of the invention is to provide a simple and easily operated cut-off valve for the oil supply which may be assembled on the drilling or other pipe which projects 20 above the well casing, in such manner as to be slid to the upper end of said pipe, tightly secured in place, and then operated to cut off the flow of oil. In this connection, a further aim is to provide the valve with a normally 25 expanded sectional ring which is screw threaded on its inner side for engagement with the usual screw threads on the pipe, means being provided for contracting said ring around the pipe when the valve is properly positioned.

A further object of the invention is to provide a head for the well casing and means for tying the above mentioned valve to said head, whereby to not only prevent the loss 35 of casing head gas, but to provide an additional anchoring means for the valve to prevent any possibility of this valve being blown from the pipe.

With the foregoing in view, the invention 40 resides in the novel construction and association of parts hereinafter described and claimed, the descriptive matter being supplemented by the accompanying drawings.

Figure 1 is a vertical sectional view of my 45 invention in operative position upon a well casing and the pipe therein.

Figures 2 and 3 are elevations, partly in section, looking in different directions.

Figures 4, 5 and 6 are horizontal sectional 50 views as indicated by lines 4-4, 5-5 and 6-6 of Fig. 1.

Figure 7 is a perspective view of the gate of the valve.

Figure 8 is a perspective view of one section of the contractible ring above referred to.

Figure 9 is a perspective view of one of the wedges which may be employed for securing the casing head to the pipe.

In the drawings above briefly described, 60 the numeral 1 designates a well casing while 2 has reference to a drilling or other pipe within and extending above said casing, the upper end of said pipe 2 being externally threaded as indicated at 3. An annular casing head 4 surrounds the pipe 2 and is secured by an appropriate coupling 5 to the casing 1 and I prefer also to provide said casing head with toothed wedges 6 slideable in grooves 7 for gripping the pipe 2. The 70 head 4 is also by preference provided with a plurality of radial set-screws 8 to be threaded into engagement with the pipe 2 as shown clearly in Fig. 5. These set-screws are shown extending through an outstanding annular 75 flange 9 with which the upper end of head 4 is provided, this flange serving to perform an additional function hereinafter set forth. The entire head 4 is split longitudinally into halves so that it may be readily applied 80 around the pipe 2, and these halves are secured together by appropriate clamping bolts 10.

Above the casing head 4, a valve casing 11 is provided, said casing being formed of 85 two sections secured together by bolts 11* so that it may be assembled around the pipe 2 in the same manner as said head 4. One section of the casing 11 is provided with a laterally extending guide 12 in which a sliding gate valve 13 is normally housed. This gate is provided with an operating screw 14 having a swivelled connection therewith and a stem 15 leads from said screw through a stuffing box 16 in the outer end of the guide 90 so that the gate 13 may be projected and retracted as desired. This gate is preferably wedge-shaped as clearly shown in Figs. 1 and 7 in order that it will tightly wedge in place when in closed position.

The valve casing 11, with the gate 13 retracted into the guide 12, is adapted to be applied to the pipe 2 in position to be slid upwardly on said pipe to a position to permit closing of said gate when discharge of 105 oil takes place through the pipe 2, and for

anchoring said casing in this last named or operative position, novel means are provided. Near its lower end, the casing 11 is formed with a circumferential internal 5 groove 17 in which a sectional ring 18 is confined, the inner side of the ring section being provided with screw-threads 19 which are adapted to engage the threads 3 of pipe 2, when the ring is contracted tightly around 10 said pipe. For so contracting ring 18, a plurality of radial set-screws 20 are provided, these set-screws being threaded through an outstanding flange 21 on the lower end of the casing 11. Other radial screws 22 pref- 15 erably pass through flange 21 for engagement with the pipe 2 to further anchor the valve casing.

In order to provide further for anchoring the casing 11 against possible blowing 20 from the end of the pipe 2, I provide a plurality of tie-rods 23 which pass through the flange 21 of said casing and the flange 9 of said casing head 4, thereby effectively anchoring said valve casing to said casing 25 head.

By employing the construction shown, the casing head 4 and the valve casing 11 may be assembled around the pipe 2 before oil is struck and said casing head may be secured to the casing 1 by the coupling 5. When the outrush of oil starts through the pipe 2, the valve casing 11 is slid upwardly along the pipe 2 until it projects above the upper end of said pipe as seen in Fig. 1. 35 The bolts 11^a are then tightened, the set-screws 20 are operated to contract the ring 18 and engage its screw-threads with the threads 3, the set-screws 22 are tightened, the wedges 6 are driven downwardly to active position, the set-screws 8 are operated 40 to tightly clamp the pipe 2, and the tie-rods 23 are applied to anchor the valve casing 11 to the casing head 4. The stem 15 may then be rotated to slowly close the 45 valve 13 to arrest the discharge of oil until a pipe line can be tapped into the upper end of the valve casing 11 and run to an appropriate reservoir. This having been done, the valve 13 may be opened to permit 50 the oil to discharge into the pipe line and reservoir so that no loss will occur. When one reservoir is filled and the pipe line must be connected with another, the valve 13 may of course be closed during this operation.

55. From the foregoing, taken in connection with the accompanying drawings, it will be seen that while my invention is of rather simple and inexpensive nature, it will be highly efficient and will fulfill a long felt 60 need in the art of well drilling. Since excellent results may be obtained from the details disclosed, they may be followed if desired, but attention is here directed to the fact that the present disclosure is for illustrative purposes only and that within the

scope of the invention as claimed, numerous changes may be made.

I claim:

1. A well capping device comprising a casing head and means for securing it to a well casing, a valve casing adapted to surround a pipe extending from said well casing, said casing head and said valve casing having outstanding projections provided with aligned openings, tie rods passing 75 through said aligned openings for anchoring said valve casing to said casing head, and a cut-off valve for said valve casing adapted to close over said pipe.

2. A well capping device comprising a 80 casing head and means for securing it to a well casing, a valve casing adapted to surround a pipe extending from said well casing, means securing said valve casing to said casing head, a cutoff valve for said 85 valve casing adapted to close over said pipe, and means for clamping said casing head on said pipe.

3. A well capping device comprising a 90 casing head and means for securing it to a well casing, a valve casing adapted to surround a threaded pipe extending from said well casing, said valve casing having an internal circumferential groove, a sectional internally threaded ring in said groove, set 95 screws threaded through the valve casing for projecting the ring sections from the groove to interengage their threads with the threads of the aforesaid pipe, and a cutoff valve for said valve casing adapted to close 100 over said pipe.

4. A well capping device comprising a valve casing formed of sections and means for clamping them together around a well pipe, said casing being adapted to be slid 105 to the upper end of the pipe when the well discharges through said pipe, a valve adapted to close across said casing over the pipe, and a normally retracted screw threaded means carried by the valve casing and 110 adapted to be projected into engagement with the usual screw threads of the pipe.

5. A well capping device comprising a valve casing formed of sections and means for clamping them together around a well 115 pipe, said casing being adapted to be slid to the upper end of the pipe when the well discharges through said pipe, a valve adapted to close across said casing over the pipe, a normally expanded sectional ring carried 120 by said valve casing and internally threaded, said casing having an internal groove receiving said ring, and set screws threaded through said casing for contracting said ring around the aforesaid pipe and engaging the screw threads of said ring with those of the pipe.

In testimony whereof I have hereunto set my hand.

ELIGAH HENRY DUCKETT.
